UNITED STATES PATENT OFFICE.

ALFONSO OLIVERAS GUERRIS, OF BARCELONA, SPAIN.

BOTTLE-DISPENSING DEVICE.

Application filed June 7, 1926, Serial No. 114,356, and in France August 5, 1925.

The methods employed up to the present for emptying beverages containing dissolved gases from their containing vessels have all the great disadvantage that the vessel must be completely emptied once it has been opened because the liquid becomes flat once the cork has been removed.

In order to overcome this fault and the disadvantages which arise from it, the applicant has designed an entirely new apparatus, of mechanical construction, with automatic tightening, enabling desired quantities of liquids of all kinds containing dissolved gases, hereinafter called aerated liquids, which are contained under pressure in a vessel, to be removed from the latter without opening the vessel. This apparatus allows the chemical properties of the liquids to be preserved for an indefinite length of time, which properties are caused to disappear or deteriorate, on account of the unavoidable evaporation which is produced, when the cork is removed, or when use is made of taps of the usual type, or of other apparatus operating under a pressure which gradually decreases.

The following description, with reference to the accompanying drawing, given by way of example, enables the manner in which the invention is carried into effect to be clearly understood.

Figure 1 is a front elevation of the piercing and outlet device of the apparatus.

Figure 2 shows the end cover of the apparatus.

Figure 3 is a general arrangement view of the apparatus, in section.

Figure 4 is a vertical section through the end cover.

Figure 5 shows an accessory perforating device forming a part of the apparatus.

Figures 6, 7, 8, 9, and 10 are various forms of closing devices.

Figures 11 and 12 refer to the same device as Figures 6 to 10 both inclusive, but adopting a different form to the former, though its function is the same.

The apparatus is composed of a piercing and outlet device, shown in Figure 1, and a pressure closing device, shown in Figure 4.

The piercing device consists of a member in the form of a pin *h*, *m*, made of brass or of another alloy of sufficient strength, the said pin being fitted and soldered or fixed by other mechanical means in the interior of the

member *e* which comprises a hollowed out or spherical portion *g*. The part of the pin extending from the said portion *g* has the form of a truncated cone of larger diameter, for a distance to the line *i*.

The pin has been made in this conical shape so that a sufficient pressure upon the closing plug of the vessel to which the apparatus is fitted may be obtained. Beyond line *i* the pin is continued in the form of a very long point. The pin is provided with a helical screw thread *k* which is inserted, by being rotated, into the cork or closing plug of the vessel, piercing the latter and assisting in this piercing action which is effected gently and without destroying or tearing away any particles of cork, wood or other compressible substance of which the plug is made. Consequently no small particles or waste portions fall inside the vessel as happens with apparatus at present in use.

After being inserted in the plug the end of the pin *h*, *m*, will be in contact with the liquid contained in the vessel and as the said pin is also hollowed out by means of an internal duct passing through the whole of its length, which thus forms an outlet duct *r* (Fig. 3), the liquid can pass out through this duct when the vessel is turned upside down, or if the pressure of the carbonic acid or other gas contained in the liquid is sufficiently great, by passing through the long orifice *L* formed in the lower part of the pin.

The hollowed out or cup shaped portion *g* is provided for the purpose of enabling the apparatus to be adjusted upon the projecting part of the plug of the vessel. This hollowed out portion is formed at the central and lower part of the member *e*. The latter is of spherical form, cut away at its base *g* and provided on either side with arms *f* extending from the outside part of the central portion, so that the whole apparatus is shaped like a dagger which facilitates the handling of the apparatus. It may in particular be held so as to be turned in the direction of rotation for piercing the plug of vessels.

Immediately beyond this hemispherical member *e*, is the "piston" of the apparatus. A cylindrical portion *d* co-operates with the cylindrical portion of the end cover shown in Figure 4. Above this is another cylindrical portion *b* of small diameter, having a number of channels, grooves or screw

threads so that it fits into the corresponding portion *s* (Figure 4). The device terminates in another cylindrical portion *a* which is smooth and of smaller diameter than the previous one and co-axial with it.

In order to assemble the apparatus, the valve carrying cap *t* (Figs. 6, 7, 8 and 10 or 11 and 12) is placed inside the end cover *C* so that the surface shown in Figure 8 or 11 rests upon the bottom *n* of the recess when the cover is inverted (Fig. 4). The rubber sleeve *q* (Fig. 9) is then placed in the cylindrical part of the end cover. The said sleeve adapts itself perfectly to the interior of this cylindrical cavity formed in the end cover and compels it to keep in the above mentioned position relatively to the valve carrier but does not exert any pressure upon it. On the contrary, the said parts are slightly separated from each other in order to prevent them from sticking together and preventing, entirely or partly, the liquid passing from the interior of the sleeve *q* towards the inner cylindrical portion of the end cover.

The interior of the end cover having been thus prepared, it is fitted upon the member shown in Figure 1, sliding over the cylindrical portion *a*. The screw threaded portion *c* enters into the corresponding female thread *s*. The cylindrical part *a* enters into the rubber sleeve *q* and fits perfectly against the latter. When the said members are thus assembled the cylinder *a* exerts a pressure upon the valve *v* which corresponds in magnitude to the number of turns given to the piston.

As shown in Figures 7 and 8, the valve carrier is provided with a number of notches *n* upon its base and the peripheral part of the cap, and it is consequently easily understood that the pressure of the cylinder *a* keeps the outlet duct *rr* of the end cover hermetically closed while the liquid in the whole of the duct *r* will be retained by the pressure of the rubber sleeve *q* and consequently that when the end cover is slightly released, the liquid will be discharged from the interior of the cylinder which surrounds the rubber sleeve and will pass over the valve carrier. At this moment the latter will be released from the action of the pressure of the cylinder *a* and will allow the liquid to pass through the notches *n*, the said liquid issuing freely through the aperture *rr*.

As shown in Figures 11 and 12, the structure of the valve carrying cap may be varied so as to obtain a perfect flowing of liquids. In Figure 11 the said device is shown by its base and adopting the shape of a star of six points the coupling angles of which are formed with arcs that determine the grooves or concave hollowing of the longitudinal walls; the inner part being hollowed to con-

tain the rubber disc, valve or tap upon which the axle of the apparatus has to operate.

The grooves of the longitudinal walls end at the same level as the rubber disc contained inside the valve carrier and permit liquid flow when the valve is open.

As an accessory member of the apparatus, the device employed for facilitating the insertion of the pin *h-m*, is shown in the drawing, in Figure 5.

The greater part of vessels containing aerated drinks are closed by means of cork plugs which are covered externally with a small cap made of white metal of sheet aluminium, tinned iron or another metal. However weak it may be, this metal offers a certain amount of resistance which in time and with continual use would spoil the pointed part of the apparatus.

In order to overcome this objection and to ensure that the point, which is adapted to be used upon compressible substances such as cork, rubber, etc. will remain in good condition, use is made according to the invention of a steel perforating tool of cylindrical form provided with a point (or needle) made of steel for perforating the said metal sheet. Through the aperture thus formed the point of the apparatus may then be inserted the plug of the vessel pierced by means of it.

Figure 5 shows the steel cylinder which comprises two cutting teeth of helical form. At the centre of the cylinder is located the needle.

This needle *x* after having pierced through the metal sheet sinks into the cork or other substance of which the plug is made and when the knives or cutting members *z* come into contact with the sheet it is sufficient to rotate the device about this point in order to remove a portion of the centre of the sheet, thus leaving an aperture through which the pin of the apparatus may be inserted without necessitating the exercise of much force.

The outlet apparatus and also its accessory device may be constructed by any mechanical means in use and any suitable materials may be employed in them. The metal parts may be made of metals already known or of alloys of empirical composition which may be suitable and for the general construction use may be made of methods currently employed in foundries.

Having now particularly described and ascertained the nature of my said invention and in what manner the same is to be performed, I declare that what I claim is:

1. In a bottle tap, the combination of a conduit having a terminal peripheral valve seat, a nozzle screwed to the conduit and a valve adapted to be loosely housed between the nozzle and the conduit terminal and

compressed against the latter by operation of the nozzle to close the same, said valve having side grooving to permit passage of fluid through the nozzle when pressure of the 5 valve is released when operating the nozzle.

2. In a bottle tap, the combination of a conduit having a terminal peripheral valve seat, a nozzle screwed to the conduit and a valve adapted to be loosely housed between 10 the nozzle and the conduit terminal and com-

pressed against the latter by operation of the nozzle to close the same, said valve having a plurality of side grooves to permit passage of fluid through the nozzle when pressure on the valve is released by operating the nozzle. 15

In testimony whereof I have signed my name to this specification.

Dated this day 27th of April, 1926.

ALFONSO OLIVERAS GUERRIS.
